HEAT EXCHANGER AND HOT WATER APPARATUS

BACKGROUND OF THE INVENTION

Field of the Invention

The present invention relates to a heat exchanger and a hot water apparatus and particularly to a heat exchanger including a baffle and a hot water apparatus.

Description of the Background Art

A heat exchanger in which a baffle is disposed in a heat transfer tube is disclosed, for example, in Japanese Patent No. 3687294 and Japanese Patent Publication No. 5-71842. The baffle described in these publications has a part of a plate-shaped member cut and erected. The baffle promotes a turbulent flow of water and/or hot water which flows through the heat transfer tube so that thermal efficiency of the heat transfer tube is improved.

Since the baffle described in the publications rotates in the heat transfer tube when it is inserted in the heat transfer tube, it is disadvantageously difficult to assemble the baffle to the inside of the heat transfer tube.

SUMMARY OF THE INVENTION

The present invention was made in view of the problem above, and an object thereof is to provide a heat exchanger in which a turbulent flow of water and/or hot water flowing through the heat transfer tube is promoted and a baffle is readily assembled to the inside of the heat transfer tube and a hot water apparatus including the same.

A heat exchanger according to the present invention includes a heat transfer tube and a baffle. Water and/or hot water flows in an internal space in the heat transfer tube. The baffle is disposed in the internal space in the heat transfer tube and configured to promote a turbulent flow in water and/or hot water in the internal space. The baffle includes a main body portion, a first protruding portion, a second protruding portion, a first wall, and a second wall. The main body portion extends in an axial direction of the heat transfer tube and divides the internal space into a first space and a second space in a radial direction of the heat transfer tube. The first protruding portion protrudes from the main body portion into the first space. The second protruding portion protrudes from the main body portion into the second space. The first wall is connected to a first end portion of the main body portion and extends in the axial direction of the heat transfer tube. The second wall is connected to a second end portion of the main body portion and extends in the axial direction of the heat transfer tube. Each of the first protruding portion and the second protruding portion is disposed between the first wall and the second wall. The first wall includes a first protruding wall and a second protruding wall. The first protruding wall protrudes into the first space with respect to the main body portion. The second protruding wall protrudes into the second space with respect to the main body portion. The second wall includes a third protruding wall and a fourth protruding wall. The third protruding wall protrudes into the first space with respect to the main body portion. The fourth protruding wall protrudes into the second space with respect to the main body portion.

According to the heat exchanger in the present invention, the first protruding portion protruding from the main body portion into the first space and the second protruding portion

2

protruding from the main body portion into the second space promote a turbulent flow of water and/or hot water flowing through the heat transfer tube. At the first end portion of the main body portion, the first protruding wall and the second protruding wall can be in contact with the heat transfer tube in the first space and the second space, and at the second end portion of the main body portion, the third protruding wall and the fourth protruding wall can be in contact with the heat transfer tube in the first space and the second space. Thus, 5 rotation of the baffle in the inside of the heat transfer tube in insertion thereof in the heat transfer tube can be suppressed. Therefore, assembly of the baffle to the inside of the heat transfer tube is facilitated.

In the heat exchanger, each of the first protruding wall, the 15 second protruding wall, the third protruding wall, and the fourth protruding wall extends in the axial direction of the heat transfer tube. Therefore, an area of contact of each of the first protruding wall, the second protruding wall, the third protruding wall, and the fourth protruding wall with the 20 inside of the heat transfer tube in the axial direction of the heat transfer tube can be increased. Rotation of the baffle in the inside of the heat transfer tube in insertion thereof in the heat transfer tube can further be suppressed.

In the heat exchanger, the first protruding wall and the 25 second protruding wall are equal to each other in length in the axial direction of the heat transfer tube. The third protruding wall and the fourth protruding wall are equal to each other in length in the axial direction of the heat transfer tube. Therefore, even when the heat transfer tube extends as 30 turning back from one direction to another opposite direction, non-uniformity between a flow in one direction of water and/or hot water flowing through the heat transfer tube and a flow thereof in another direction can be suppressed.

In the heat exchanger, the first protruding wall and the 35 third protruding wall are displaced from each other and the second protruding wall and the fourth protruding wall are displaced from each other in a direction in which the first end portion and the second end portion of the main body portion are opposed to each other. Therefore, any of the first 40 protruding wall and the third protruding wall and any of the second protruding wall and the fourth protruding wall can be in contact with the heat transfer tube in both of the first space and the second space. Thus, rotation of the baffle in the inside of the heat transfer tube even while any one of the first 45 protruding wall and the third protruding wall is inserted in the heat transfer tube but any the other is not inserted in the heat transfer tube can be suppressed.

In the heat exchanger, the first protruding wall and the 50 third protruding wall face each other and the second protruding wall and the fourth protruding wall face each other in a direction in which the first end portion and the second end portion of the main body portion are opposed to each other. Therefore, while any one of a set of the first protruding wall and the third protruding wall and a set of the second 55 protruding wall and the fourth protruding wall is inserted in the heat transfer tube but any the other set is not inserted in the heat transfer tube, contact with the heat transfer tube can be made only in one of the first space and the second space. Thus, while any one of the set of the first protruding wall and the third protruding wall and the set of the second protruding wall and the fourth protruding wall is inserted in the heat transfer tube but any the other set is not inserted in the heat transfer tube, the baffle can smoothly be inserted in the heat transfer tube.

In the heat exchanger, the first protruding portion and the 60 second protruding portion are connected to the main body portion as being aligned in a direction in which the first end

portion and the second end portion of the main body portion are opposed to each other. Therefore, at a position where the first protruding portion and the second protruding portion are connected to the main body portion as being aligned in the direction in which the first end portion and the second end portion of the main body portion are opposed to each other, a turbulent flow of water and/or hot water in both of the first space and the second space is promoted. A turbulent flow of water and/or hot water in the whole internal space is thus promoted.

In the heat exchanger, the baffle includes a first hook portion for fixation to the heat transfer tube. The first hook portion is provided in a first wall portion and a second wall portion and constructed to project to increase a distance between the first wall portion and the second wall portion from a front end portion toward a rear end portion of the baffle in the axial direction of the heat transfer tube and to thereafter decrease the distance between the first wall portion and the second wall portion. Therefore, the first hook portion can fix the baffle to the heat transfer tube. The first hook portion can elastically deform so as to decrease the distance between the first wall portion and the second wall portion while the first hook portion is inserted in the internal space in the heat transfer tube. When the first hook portion is moved out of the internal space, it is restored and can be hooked to one end surface in the axial direction of the heat transfer tube. Therefore, the baffle is readily fixed to the heat transfer tube.

In the heat exchanger, the baffle includes a second hook portion for fixation to the heat transfer tube. The second hook portion is provided in the first wall portion and the second wall portion and constructed to project to increase the distance between the first wall portion and the second wall portion in the rear end portion of the baffle and to thereafter project toward the front end portion of the baffle. Therefore, the second hook portion can fix the baffle to the heat transfer tube. Since the baffle cannot be inserted in the heat transfer tube from a side of the rear end portion due to the second hook portion, a direction of insertion of the baffle into the heat transfer tube can be restricted. Insertion of the baffle in a reverse direction can thus be prevented.

In the heat exchanger, the baffle includes a second hook portion for fixation to the heat transfer tube. The second hook portion is provided in the first wall portion and the second wall portion and constructed to project to increase the distance between the first wall portion and the second wall portion from the rear end portion toward the front end portion of the baffle in the axial direction of the heat transfer tube and to thereafter decrease the distance between the first wall portion and the second wall portion. Therefore, the second hook portion can fix the baffle to the heat transfer tube. The second hook portion can elastically deform so as to decrease the distance between the first wall portion and the second wall portion while the second hook portion is inserted in the internal space in the heat transfer tube. When the second hook portion is moved out of the internal space, it is restored and can be hooked to the other end surface in the axial direction of the heat transfer tube. Therefore, the baffle is readily fixed to the heat transfer tube. The baffle can be inserted in the inside of the heat transfer tube from any of the front end portion and the rear end portion of the baffle.

In the heat exchanger, the baffle includes a reinforcement portion which connects the first wall and the second wall to each other and is disposed at a distance from the main body portion in the axial direction of the heat transfer tube. The reinforcement portion is greater in width than the main body

portion in the axial direction of the heat transfer tube. The reinforcement portion can thus reinforce the baffle.

In the heat exchanger, the internal space has an elliptical cross-section in the radial direction of the heat transfer tube.

5 A length from a tip end of the first protruding portion in the first space to a tip end of the second protruding portion in the second space when the first protruding portion and the second protruding portion are viewed in the axial direction of the heat transfer tube is equal to or shorter than a length 10 of a minor axis of the elliptical cross-section. Therefore, contact of the first protruding portion and the second protruding portion with the heat transfer tube in insertion of the baffle in the heat transfer tube is suppressed. The baffle is thus readily inserted in the heat transfer tube. Damage to the first protruding portion and the second protruding portion due to contact of the first protruding portion and the second protruding portion with the heat transfer tube in insertion of the baffle in the heat transfer tube can be suppressed.

20 A hot water apparatus according to the present invention includes the heat exchanger described above and a burner which generates a gas for heating to be supplied to the heat exchanger. According to the hot water apparatus in the present invention, a hot water apparatus including a heat 25 exchanger in which a turbulent flow of water and/or hot water flowing through the heat transfer tube is promoted and a baffle is readily assembled to the inside of the heat transfer tube can be provided.

25 The foregoing and other objects, features, aspects and 30 advantages of the present invention will become more apparent from the following detailed description of the present invention when taken in conjunction with the accompanying drawings.

BRIEF DESCRIPTION OF THE DRAWINGS

35 FIG. 1 is a diagram schematically showing a construction of a hot water apparatus in one embodiment of the present invention.

40 FIG. 2 is a perspective view schematically showing a construction of a sensible heat recovery heat exchanger and a latent heat recovery heat exchanger in one embodiment of the present invention.

45 FIG. 3 is a perspective view schematically showing the construction of the sensible heat recovery heat exchanger in one embodiment of the present invention.

50 FIG. 4 is a cross-sectional view schematically showing a construction of the sensible heat recovery heat exchanger in one embodiment of the present invention.

55 FIG. 5 is a cross-sectional view showing a state of attachment of a baffle to an end portion of a heat transfer tube in one embodiment of the present invention.

60 FIG. 6 is a cross-sectional view showing a state of attachment of the baffle to the heat transfer tube in one embodiment of the present invention.

65 FIG. 7 is a perspective view schematically showing a construction of the baffle in one embodiment of the present invention.

70 FIG. 8 is a side view schematically showing the construction of the baffle in one embodiment of the present invention.

75 FIG. 9 is a front view schematically showing the construction of the baffle in one embodiment of the present invention.

80 FIG. 10 is a cross-sectional view schematically showing a flow of water and/or hot water in the inside of the heat transfer tube in one embodiment of the present invention.

FIG. 11 is a perspective view schematically showing a construction of a first modification of the baffle.

FIG. 12 is a perspective view schematically showing a construction of a second modification of the baffle.

FIG. 13 is a cross-sectional view schematically showing a construction of a third modification of the baffle.

DESCRIPTION OF THE PREFERRED EMBODIMENTS

An embodiment of the present invention will be described below with reference to the drawings.

A construction of a hot water apparatus in one embodiment of the present invention will initially be described with reference to FIG. 1.

As shown in FIG. 1, a hot water apparatus 100 in the present embodiment mainly includes a sensible heat recovery heat exchanger (primary heat exchanger) 10, an ignition plug 14, a latent heat recovery heat exchanger (secondary heat exchanger) 20, a burner 30, a chamber 31, a fan assembly 32, a duct 33, a venturi 34, an orifice 35, a gas valve 36, a pipe 40, a bypass pipe 41, a three-way valve 42, a liquid to liquid heat exchanger 43, a hydronic pipe 44, and a housing 50. All of components except for housing 50 among the components above are disposed in housing 50. The components are similar to those which have conventionally been known, except for sensible heat recovery heat exchanger (primary heat exchanger) 10.

A fuel gas flows to venturi 34 through gas valve 36 and orifice 35. A mixture gas mixed in venturi 34 is sent to fan assembly 32. Fan assembly 32 is configured to supply the mixture gas to burner 30.

Fan assembly 32 is connected to chamber 31 and chamber 31 is connected to burner 30. The mixture gas supplied from fan assembly 32 is sent through chamber 31 to burner 30.

Burner 30 is configured to generate a gas for heating to be supplied to sensible heat recovery heat exchanger (heat exchanger) 10. The mixture gas issued from burner 30 is ignited by ignition plug 14 and becomes the combustion gas.

Burner 30, sensible heat recovery heat exchanger 10, and latent heat recovery heat exchanger 20 are connected such that the combustion gas sequentially passes through sensible heat recovery heat exchanger 10 and latent heat recovery heat exchanger 20 and exchanges heat with water and/or hot water. Duct 33 is connected to latent heat recovery heat exchanger 20 and duct 33 extends to the outside of housing 50. The combustion gas which has passed through latent heat recovery heat exchanger 20 is thus emitted to the outside of housing 50 through duct 33.

A part of pipe 40 on a hot water exit side relative to sensible heat recovery heat exchanger 10 and bypass pipe 41 are connected to each other by three-way valve 42. Liquid to liquid heat exchanger 43 is connected to bypass pipe 41. As warm water which flows in liquid to liquid heat exchanger 43 flows outside hydronic pipe 44, heat can be exchanged between warm water which flows in liquid to liquid heat exchanger 43 and warm water which flows in hydronic pipe 44.

A construction of sensible heat recovery heat exchanger (heat exchanger) 10 included in hot water apparatus 100 will now be described with reference to FIGS. 2 to 4.

As shown in FIG. 2, sensible heat recovery heat exchanger 10 in the present embodiment mainly includes a case 11, a header 12, a heat transfer tube (heat absorption pipe: FIGS. 3 and 4) 13, a fin 16 (FIG. 4), a pressing member 17, a fixing member 18, and a baffle 19 (FIG. 4).

Case 11 includes a first sidewall 11a, a second sidewall 11b, a third sidewall 11c, and a fourth sidewall 11d. First sidewall 11a to fourth sidewall 11d are connected to form a quadrangular frame.

Case 11 in a form of the frame opens upward and downward. The combustion gas can thus be supplied to the inside of case 11 through the upper opening of case 11. The combustion gas can be exhausted to the outside of case 11 through the lower opening of case 11.

Header 12 is provided on an outer surface of first sidewall 11a. A joint 13a on a water entry side and a joint 13b on the hot water exit side are attached to header 12 provided on the outer surface of first sidewall 11a. A not-shown header 12 is provided also on an outer surface of third sidewall 11c.

As shown in FIG. 3, header 12 provided on the outer surface of first sidewall 11a and header 12 provided on the outer surface of third sidewall 11c are connected to each other through a plurality of heat transfer tubes 13. The plurality of heat transfer tubes 13 include heat transfer tubes 13 located in the inside of case 11 and heat transfer tubes 13 located outside case 11.

As shown in FIG. 4, heat transfer tube 13 is configured to allow water and/or hot water to flow in an internal space IS. In the present embodiment, heat transfer tube 13 is an elliptical tube. Internal space IS has an elliptical cross-section in a radial direction of heat transfer tube 13.

Baffle 19 is disposed in internal space IS in heat transfer tube 13. Baffle 19 is configured to promote a turbulent flow in water and/or hot water in internal space IS in heat transfer tube 13. In the present embodiment, each of a plurality of baffles 19 is disposed in internal space IS in each of the plurality of heat transfer tubes 13 located in case 11.

A flow of water and/or hot water which flows through headers 12 and heat transfer tubes 13 is, for example, as follows.

Water and/or hot water which comes in from joint 13a on the water entry side enters heat transfer tube 13 located in the inside of case 11 through header 12 provided on a side closest to one end of the outer surface of first sidewall 11a. Water and/or hot water which enters heat transfer tube 13 reaches not-shown header 12 provided on the outer surface of third sidewall 11c. Water and/or hot water which reaches header 12 provided on the outer surface of third sidewall 11c reaches header 12 provided on the outer surface of first sidewall 11a through another heat transfer tube 13 connected to header 12.

Thus, water and/or hot water moves from a side of first sidewall 11a toward third sidewall 11c and thereafter turns back from the side of third sidewall 11c toward first sidewall 11a. Thereafter, water and/or hot water flows as repeating turning back toward third sidewall 11c and turning back toward first sidewall 11a.

As shown in FIG. 2, water and/or hot water which reaches header 12 provided on a side closest to the other end of the outer surface of first sidewall 11a reaches header 12 provided on the outer surface of third sidewall 11c through heat transfer tube 13 provided on an outer surface of second sidewall 11b.

As shown in FIG. 3, water and/or hot water which reaches header 12 provided on the outer surface of third sidewall 11c reaches header 12 provided on the outer surface of first sidewall 11a through heat transfer tube 13 provided on an outer surface of fourth sidewall 11d and finally exits from joint 13b on the side of hot water.

As shown in FIG. 4, a plurality of fins 16 are connected to outer circumferential surfaces of heat transfer tubes 13

located in the inside of case 11. FIG. 3 does not show fins for the sake of brevity of description.

Baffle 19 will now be described in further detail with reference to FIGS. 4 to 10.

As shown in FIGS. 4 and 6, baffle 19 includes a main body portion 19a, a first protruding portion 19b, a second protruding portion 19c, a first wall 19d, a second wall 19e, a reinforcement portion 19f, and an opening 19g. In the present embodiment, baffle 19 includes a plurality of main body portions 19a, a plurality of first protruding portions 19b, a plurality of second protruding portions 19c, a plurality of reinforcement portions 19f, and a plurality of openings 19g.

Main body portion 19a extends in the axial direction of heat transfer tube 13. Main body portion 19a divides internal space IS into a first space IS1 and a second space IS2 in the radial direction of heat transfer tube 13. Main body portion 19a is constructed in a form of a flat plate. Main body portion 19a has a constant width in the axial direction of heat transfer tube 13.

First protruding portion 19b protrudes from main body portion 19a into first space IS1 (one side of internal space IS). Second protruding portion 19c protrudes from main body portion 19a into second space IS2 (the other side of internal space IS). First protruding portion 19b and second protruding portion 19c protrude in a direction diagonal to the centerline in the axial direction of heat transfer tube 13.

Each of first protruding portion 19b and second protruding portion 19c is disposed between first wall 19d and second wall 19e. First protruding portion 19b and second protruding portion 19c are connected to main body portion 19a as being aligned in a direction in which a first end portion 19a1 and a second end portion 19a2 of main body portion 19a are opposed to each other. At a position intermediate in a direction of a short side of baffle 19, directions of protrusion of first protruding portion 19b and second protruding portion 19c with respect to main body portion 19a are reversed. In the axial direction of heat transfer tube 13, first protruding portion 19b and second protruding portion 19c are connected to respective opposing sides of one main body portion 19a.

First wall 19d is connected to first end portion 19a1 of main body portion 19a. First wall 19d extends in the axial direction of heat transfer tube 13. First wall 19d has a first protruding wall 19d1 and a second protruding wall 19d2. First protruding wall 19d1 protrudes from main body portion 19a into first space IS1. Second protruding wall 19d2 protrudes from main body portion 19a into second space IS2.

Second wall 19e is connected to second end portion 19a2 of main body portion 19a. Second wall 19e extends in the axial direction of heat transfer tube 13. Second wall 19e has a third protruding wall 19e1 and a fourth protruding wall 19e2. Third protruding wall 19e1 protrudes from main body portion 19a into first space IS1. Fourth protruding wall 19e2 protrudes from main body portion 19a into second space IS2.

Main body portion 19a, reinforcement portion 19f, and opening 19g are disposed as being aligned in the axial direction of heat transfer tube 13. Reinforcement portion 19f connects first wall 19d and second wall 19e to each other. Reinforcement portion 19f is disposed at a distance from main body portion 19a in the axial direction of heat transfer tube 13. Reinforcement portion 19f is greater in width than main body portion 19a in the axial direction of heat transfer

tube 13. Reinforcement portion 19f is disposed between two main body portions 19a adjacent in the axial direction of heat transfer tube 13.

Opening 19g is disposed between main body portion 19a and reinforcement portion 19f in the axial direction of heat transfer tube 13. Opening 19g passes through main body portion 19a and reinforcement portion 19f in a direction of thickness of each of them. First space IS1 and second space IS2 in heat transfer tube 13 communicate with each other through opening 19g.

As shown in FIGS. 4 and 5, a length H from a tip end of first protruding portion 19b in first space IS1 to a tip end of second protruding portion 19c in second space IS2 when first protruding portion 19b and second protruding portion 19c are viewed in the axial direction of heat transfer tube 13 is equal to or shorter than a length of a minor axis D of the elliptical cross-section of heat transfer tube 13.

As shown in FIGS. 5 and 9, first protruding portion 19b is greater in height than first protruding wall 19d1 and third protruding wall 19e1 when first protruding portion 19b is viewed in the axial direction of heat transfer tube 13. Second protruding portion 19c is greater in height than second protruding wall 19d2 and fourth protruding wall 19e2 when second protruding portion 19c is viewed in the axial direction of heat transfer tube 13.

As shown in FIGS. 6 and 7, each of first protruding wall 19d1, second protruding wall 19d2, third protruding wall 19e1, and fourth protruding wall 19e2 extends in the axial direction of heat transfer tube 13. In a direction in which first end portion 19a1 and second end portion 19a2 of main body portion 19a are opposed to each other, first protruding wall 19d1 and third protruding wall 19e1 are displaced from each other and second protruding wall 19d2 and fourth protruding wall 19e2 are displaced from each other. At a position intermediate in a longitudinal direction of baffle 19, directions of protrusion of first wall 19d and second wall 19e with respect to main body portion 19a are reversed.

As shown in FIGS. 6 and 8, first protruding wall 19d1 and second protruding wall 19d2 are equal to each other in length in the axial direction of heat transfer tube 13. Third protruding wall 19e1 and fourth protruding wall 19e2 are equal to each other in length in the axial direction of heat transfer tube 13.

As shown in FIGS. 6 and 7, baffle 19 has a first hook portion S1 for fixation to heat transfer tube 13. First hook portion S1 is provided in a front end portion FP of baffle 19 in the axial direction of heat transfer tube 13. First hook portion S1 is provided in first wall 19d and second wall 19e. First hook portion S1 is constructed to project to increase a distance between first wall 19d and second wall 19e from front end portion FP toward a rear end portion BP of baffle 19 in the axial direction of heat transfer tube 13 and to thereafter decrease the distance between first wall 19d and second wall 19e. First hook portion S1 is hooked to one end surface of heat transfer tube 13 in the axial direction of heat transfer tube 13. On a side of front end portion FP of baffle 19, main body portion 19a is not formed between end portions of first protruding wall 19d1 and fourth protruding wall 19e2.

As shown in FIGS. 5 and 6, baffle 19 has a second hook portion S2 for fixation to heat transfer tube 13. Second hook portion S2 is provided in rear end portion BP of baffle 19 in the axial direction of heat transfer tube 13. As shown in FIGS. 6 and 7, second hook portion S2 is provided in first wall 19d and second wall 19e. Second hook portion S2 is constructed to project to increase the distance between first wall 19d and second wall 19e in rear end portion BP of baffle

19 and to thereafter project toward front end portion FP of baffle 19. Second hook portion S2 is hooked to the other end surface of heat transfer tube 13 in the axial direction of heat transfer tube 13. On a side of rear end portion BP of baffle 19, main body portion 19a is formed also between end portions of second protruding wall 19d2 and third protruding wall 19e1.

As shown in FIGS. 6 and 10, some of water and/or hot water flowing through heat transfer tube 13 flows as meandering through first space IS1 and second space IS2 in heat transfer tube 13 through openings 19g in baffle 19. In first space IS1 in internal space IS in heat transfer tube 13, a turbulent flow of water and/or hot water flowing through heat transfer tube 13 is promoted by first protruding portions 19b. In second space IS2 in internal space IS in heat transfer tube 13, a turbulent flow of water and/or hot water flowing through heat transfer tube 13 is promoted by second protruding portions 19c.

Functions and effects of the present embodiment will now be described.

According to sensible heat recovery heat exchanger (heat exchanger) 10 in the present embodiment, first protruding portion 19b protruding from main body portion 19a of baffle 19 into first space IS1 and second protruding portion 19c protruding from main body portion 19a into second space IS2 promote a turbulent flow of water and/or hot water flowing through heat transfer tube 13. At first end portion 19a1 of main body portion 19a, first protruding wall 19d1 and second protruding wall 19d2 can be in contact with heat transfer tube 13 in first space IS1 and second space IS2, and at second end portion 19a2 of main body portion 19a, third protruding wall 19e1 and fourth protruding wall 19e2 can be in contact with heat transfer tube 13 in first space IS1 and second space IS2. Thus, rotation of baffle 19 in heat transfer tube 13 in insertion thereof in heat transfer tube 13 is suppressed. Therefore, assembly of baffle 19 to the inside of heat transfer tube 13 is facilitated.

According to sensible heat recovery heat exchanger (heat exchanger) 10 in the present embodiment, each of first protruding wall 19d1, second protruding wall 19d2, third protruding wall 19e1, and fourth protruding wall 19e2 extends in the axial direction of heat transfer tube 13. Therefore, an area of contact of each protruding wall with the inside of heat transfer tube 13 in the axial direction of heat transfer tube 13 can be increased. Rotation of baffle 19 in heat transfer tube 13 in insertion thereof in heat transfer tube 13 is thus further suppressed.

According to sensible heat recovery heat exchanger (heat exchanger) 10 in the present embodiment, first protruding wall 19d1 and second protruding wall 19d2 are equal to each other in length in the axial direction of heat transfer tube 13 and third protruding wall 19e1 and fourth protruding wall 19e2 are equal to each other in length in the axial direction of heat transfer tube 13. Therefore, even when heat transfer tube 13 extends as turning back from one direction to another opposite direction, non-uniformity between a flow in one direction of water and/or hot water flowing through heat transfer tube 13 and a flow thereof in another direction can be suppressed.

According to sensible heat recovery heat exchanger (heat exchanger) 10 in the present embodiment, first protruding wall 19d1 and third protruding wall 19e1 are displaced from each other and second protruding wall 19d2 and fourth protruding wall 19e2 are displaced from each other in a direction in which first end portion 19a1 and second end portion 19a2 of main body portion 19a are opposed to each other. Therefore, any of first protruding wall 19d1 and third

protruding wall 19e1 and any of second protruding wall 19d2 and fourth protruding wall 19e2 can be in contact with heat transfer tube 13 in both of first space IS1 and second space IS2. Thus, rotation of baffle 19 in heat transfer tube 13 even while any one of first protruding wall 19d1 and third protruding wall 19e1 is inserted in the heat transfer tube but any the other is not inserted in heat transfer tube 13 is suppressed.

According to sensible heat recovery heat exchanger (heat exchanger) 10 in the present embodiment, first protruding portion 19b and second protruding portion 19c are connected to main body portion 19a as being aligned in a direction in which first end portion 19a1 and second end portion 19a2 of main body portion 19a are opposed to each other. Therefore, at a position where first protruding portion 19b and second protruding portion 19c are connected to main body portion 19a, a turbulent flow of water and/or hot water in both of first space IS1 and second space IS2 is promoted. A turbulent flow of water and/or hot water in whole internal space IS is thus promoted.

According to sensible heat recovery heat exchanger (heat exchanger) 10 in the present embodiment, first hook portion S1 can fix baffle 19 to heat transfer tube 13. First hook portion S1 can elastically deform to increase the distance between first wall 19d and second wall 19e while the first hook portion is inserted in internal space IS in heat transfer tube 13. When the first hook portion is moved out of internal space IS, it is restored and can be hooked to one end surface in the axial direction of heat transfer tube 13. Therefore, baffle 19 is readily fixed to heat transfer tube 13. Since main body portion 19a is not formed between end portions of first protruding wall 19d1 and fourth protruding wall 19e2 on the side of front end portion FP of baffle 19, elastic deformation is easy.

According to sensible heat recovery heat exchanger (heat exchanger) 10 in the present embodiment, second hook portion S2 can fix baffle 19 to heat transfer tube 13. Since baffle 19 cannot be inserted in heat transfer tube 13 from the side of rear end portion BP due to second hook portion S2, a direction of insertion of baffle 19 into heat transfer tube 13 can be restricted. Insertion of baffle 19 in a reverse direction can thus be prevented. Since main body portion 19a is formed also between end portions of second protruding wall 19d2 and third protruding wall 19e1 on the side of rear end portion BP of baffle 19, the end portions are less likely to elastically deform. Therefore, unintended introduction of second hook portion S2 into heat transfer tube 13 can be suppressed.

According to sensible heat recovery heat exchanger (heat exchanger) 10 in the present embodiment, since reinforcement portion 19f is greater in width than main body portion 19a in the axial direction of heat transfer tube 13, reinforcement portion 19f can reinforce baffle 19.

According to sensible heat recovery heat exchanger (heat exchanger) 10 in the present embodiment, a length from the tip end of first protruding portion 19b in first space IS1 to the tip end of second protruding portion 19c in second space IS2 when first protruding portion 19b and second protruding portion 19c are viewed in the axial direction of heat transfer tube 13 is equal to or shorter than a length of the minor axis of the elliptical cross-section of heat transfer tube 13. Therefore, contact of first protruding portion 19b and second protruding portion 19c with heat transfer tube 13 in insertion of baffle 19 into heat transfer tube 13 is suppressed. Baffle 19 is thus readily inserted in heat transfer tube 13. Damage to first protruding portion 19b and second protruding portion 19c due to contact of first protruding portion 19b and second

11

protruding portion **19c** with heat transfer tube **13** in insertion of baffle **19** into heat transfer tube **13** can be suppressed.

A hot water apparatus **100** in the present embodiment includes sensible heat recovery heat exchanger (heat exchanger) **10** and burner **30** which generates a gas for heating to be supplied to sensible heat recovery heat exchanger (heat exchanger) **10**. According to hot water apparatus **100** in the present embodiment, hot water apparatus **100** including sensible heat recovery heat exchanger (heat exchanger) **10** in which a turbulent flow of water and/or hot water flowing through heat transfer tube **13** is promoted and baffle **19** is readily assembled to the inside of heat transfer tube **13** can be provided.

Various modifications of baffle **19** in the present embodiment will now be described with reference to FIGS. 11 to 13. Since various modifications are the same in construction as the present embodiment unless otherwise specified, the same elements have the same reference characters allotted and description thereof will not be repeated.

As shown in FIG. 11, in a first modification of baffle **19**, a length of first protruding wall **19d1**, second protruding wall **19d2**, third protruding wall **19e1**, and fourth protruding wall **19e2** in the axial direction of heat transfer tube **13** is different from that in the present embodiment above. In the first modification of baffle **19**, first protruding wall **19d1**, second protruding wall **19d2**, third protruding wall **19e1**, and fourth protruding wall **19e2** are disposed at opposing end portions of baffle **19** in the axial direction of heat transfer tube **13** and not disposed in a central portion.

According to the first modification of baffle **19**, since first protruding wall **19d1**, second protruding wall **19d2**, third protruding wall **19e1**, and fourth protruding wall **19e2** are disposed in opposing end portions of baffle **19** in the axial direction of heat transfer tube **13**, rotation of baffle **19** in heat transfer tube **13** in insertion thereof in heat transfer tube **13** is suppressed. Since first protruding wall **19d1**, second protruding wall **19d2**, third protruding wall **19e1**, and fourth protruding wall **19e2** are not disposed in the central portion of baffle **19** in the axial direction of heat transfer tube **13**, the central portion cannot be in contact with heat transfer tube **13**. The central portion of baffle **19** can thus smoothly be inserted in heat transfer tube **13**. Since each protruding wall is not disposed in the central portion of baffle **19**, cost for a material for baffle **19** can be reduced.

As shown in FIG. 12, in a second modification of baffle **19**, a combination of directions of protrusion of first protruding wall **19d1**, second protruding wall **19d2**, third protruding wall **19e1**, and fourth protruding wall **19e2** is different from that in the embodiment above. In the second modification of baffle **19**, in the direction in which first end portion **19a1** and second end portion **19a2** of main body portion **19a** of baffle **19** are opposed to each other, first protruding wall **19d1** and third protruding wall **19e1** face each other and second protruding wall **19d2** and fourth protruding wall **19e2** face each other.

According to the second modification of baffle **19**, while any one of a set of first protruding wall **19d1** and third protruding wall **19e1** and a set of second protruding wall **19d2** and fourth protruding wall **19e2** is inserted in heat transfer tube **13** but any the other set is not inserted in heat transfer tube **13**, contact with heat transfer tube **13** can be made only in one of first space **IS1** and second space **IS2**. Thus, while any one of the set of first protruding wall **19d1** and third protruding wall **19e1** and the set of second protruding wall **19d2** and fourth protruding wall **19e2** is inserted in heat transfer tube **13** but any the other set is not

12

inserted in heat transfer tube **13**, baffle **19** can smoothly be inserted in heat transfer tube **13**.

As shown in FIG. 13, in a third modification of baffle **19**, a construction of second hook portion **S2** is different from that in the present embodiment above. In the third modification of baffle **19**, baffle **19** has second hook portion **S2** for fixation to heat transfer tube **13**. Second hook portion **S2** is provided in rear end portion **BP** of baffle **19** in the axial direction of heat transfer tube **13**. Second hook portion **S2** is provided in first wall **19d** and second wall **19e**. Second hook portion **S2** is constructed to project to increase the distance between first wall **19d** and second wall **19e** from rear end portion **BP** toward front end portion **FP** of baffle **19** in the axial direction of heat transfer tube **13** and to decrease the distance between first wall **19d** and second wall **19e**. Second hook portion **S2** is hooked to the other end surface of heat transfer tube **13** in the axial direction of heat transfer tube **13**.

According to the third modification of baffle **19**, second hook portion **S2** can fix baffle **19** to heat transfer tube **13**. Second hook portion **S2** can elastically deform to decrease the distance between first wall **19d** and second wall **19e** while the second hook portion is inserted in internal space **IS** in heat transfer tube **13**. When the second hook portion is moved out of internal space **IS**, it is restored and can be hooked to the other end surface in the axial direction of heat transfer tube **13**. Baffle **19** is thus readily fixed to heat transfer tube **13**. Baffle **19** can be inserted in heat transfer tube **13** from any of front end portion **FP** and rear end portion **BP** of baffle **19**.

Though an embodiment of the present invention has been described, it should be understood that the embodiment disclosed herein is illustrative and non-restrictive in every respect. The scope of the present invention is defined by the terms of the claims and is intended to include any modifications within the scope and meaning equivalent to the terms of the claims.

What is claimed is:

1. A heat exchanger comprising:
a heat transfer tube in which water and/or hot water flows in an internal space; and
a baffle disposed in the internal space in the heat transfer tube, the baffle promoting a turbulent flow in the water and/or hot water in the internal space,
the baffle including
plural main body portions which extend in an axial direction of the heat transfer tube and divide the internal space into a first space and a second space in a radial direction of the heat transfer tube,
plural first protruding portions, each of which protrudes from one of the main body portions into the first space,
plural second protruding portions, each of which protrudes from one of the main body portions into the second space,
a first wall connected to a first end portion of each main body portion and extending in the axial direction of the heat transfer tube, and
a second wall connected to a second end portion of each main body portion and extending in the axial direction of the heat transfer tube,
each of the first protruding portions and the second protruding portions being disposed between the first wall and the second wall,
the first wall including a first protruding wall protruding into the first space with respect to the main body

13

portions and a second protruding wall protruding into the second space with respect to the main body portions, and

the second wall including a third protruding wall protruding into the first space with respect to the main body portions and a fourth protruding wall protruding into the second space with respect to the main body portions,

wherein at least one of the first protruding wall, the second protruding wall, the third protruding wall, and the fourth protruding wall has a length in the axial direction of the heat transfer tube that exceeds at least one of a distance between consecutive first protruding portions and a distance between consecutive second protruding portions.

2. The heat exchanger according to claim 1, wherein each of the first protruding wall, the second protruding wall, the third protruding wall, and the fourth protruding wall extends in the axial direction of the heat transfer tube.

3. The heat exchanger according to claim 2, wherein the first protruding wall and the second protruding wall are equal to each other in length in the axial direction of the heat transfer tube, and the third protruding wall and the fourth protruding wall are equal to each other in length in the axial direction of the heat transfer tube.

4. The heat exchanger according to claim 1, wherein the first protruding wall and the third protruding wall are displaced from each other and the second protruding wall and the fourth protruding wall are displaced from each other in a direction in which the first end portion and the second end portion of each main body portion are opposed to each other.

5. The heat exchanger according to claim 1, wherein the first protruding wall and the third protruding wall face each other and the second protruding wall and the fourth protruding wall face each other in a direction in which the first end portion and the second end portion of each main body portion are opposed to each other.

6. The heat exchanger according to claim 1, wherein the first protruding portions and the second protruding portions are aligned in a direction in which the first end portion and the second end portion of each main body portion are opposed to each other.

7. The heat exchanger according to claim 1, wherein the baffle includes a first hook portion for fixation to the heat transfer tube, and

the first hook portion is provided in the first wall and the second wall and includes a first portion that has a shape that increases a distance between the first wall and the second wall and a second portion that has a shape that decreases the distance between the first wall and the second wall, the first portion of the first hook portion being closer to a front end portion of the baffle than the second portion of the first hook portion.

8. The heat exchanger according to claim 7, wherein the baffle includes a second hook portion for fixation to the heat transfer tube, and the second hook portion is provided in the first wall and the second wall and includes a first portion that projects outwardly in the radial direction of the heat transfer tube from at least one of the first wall and the second wall and a second portion that extends from an outward most end of the first portion of the second hook portion toward the front end portion of the baffle.

14

9. The heat exchanger according to claim 7, wherein the baffle includes a second hook portion for fixation to the heat transfer tube, and

the second hook portion is provided in the first wall and the second wall and includes a first portion that has a shape that increases the distance between the first wall and the second wall and a second portion that has a shape that decreases the distance between the first wall and the second wall, the first portion of the second hook portion being closer to a rear end portion of the baffle than the second portion of the second hook portion.

10. The heat exchanger according to claim 1, wherein the baffle includes a reinforcement portion which connects the first wall and the second wall to each other and is disposed at a distance from each main body portion in the axial direction of the heat transfer tube, and

the reinforcement portion is greater in width than each main body portion in the axial direction of the heat transfer tube.

11. The heat exchanger according to claim 1, wherein the internal space has an elliptical cross-section in the radial direction of the heat transfer tube, and

a length from a tip end of each first protruding portion in the first space to a tip end of each second protruding portion in the second space when the first protruding portions and the second protruding portions are viewed in the axial direction of the heat transfer tube is equal to or shorter than a length of a minor axis of the elliptical cross-section.

12. A hot water apparatus comprising:
the heat exchanger according to claim 1; and
a burner which generates a gas for heating to be supplied to the heat exchanger.

13. A heat exchanger comprising:
a heat transfer tube in which water and/or hot water flows in an internal space; and
a baffle disposed in the internal space in the heat transfer tube, the baffle promoting a turbulent flow in the water and/or hot water in the internal space,

the baffle including
plural main body portions which extend in an axial direction of the heat transfer tube and divide the internal space into a first space and a second space in a radial direction of the heat transfer tube,
plural first protruding portions, each of which protrudes from one of the main body portions into the first space,

plural second protruding portions, each of which protrudes from one of the main body portions into the second space,

a first wall connected to a first end portion of each main body portion and extending in the axial direction of the heat transfer tube,

a second wall connected to a second end portion of each main body portion and extending in the axial direction of the heat transfer tube, and

a reinforcement portion disposed between two consecutive main body portions,
each of the first protruding portions and the second protruding portions being disposed between the first wall and the second wall,
the first wall including a first protruding wall protruding into the first space with respect to the main body portions and a second protruding wall protruding into the second space with respect to the main body portions, and

the second wall including a third protruding wall protruding into the first space with respect to the main body portions and a fourth protruding wall protruding into the second space with respect to the main body portions, wherein

5

each of the two consecutive main body portions is separated from the reinforcement portion in the axial direction of the heat transfer tube by an opening that extends an entire distance between the first wall and the second wall in a radial direction of the heat transfer tube, and 10 at least one of the first protruding wall, the second protruding wall, the third protruding wall, and the fourth protruding wall has a length in the axial direction of the heat transfer tube that exceeds at least one of a distance between consecutive first protruding portions 15 and a distance between consecutive second protruding portions.
